OLIVER S. JENNINGS, OF BROOKLYN, NEW YORK, ASSIGNOR TO WESTINGHOUSE ELECTRIC & MANUFACTURING COMPANY, A CORPORATION OF PENNSYLVANIA.

SWITCH BOX.

Application filed October 27, 1920. Serial No. 420,047.

My invention relates to switches and particularly to enclosed switches wherein the switch mechanism is actuated by an exteriorly-extending operating shaft or handle.

An object of the invention is to provide a simple, inexpensive and readily attachable mechanism which may be applied to the operating shaft of the simple handle-operated enclosed-switch mechanism, whereby the switch may be opened and closed with a snap action.

A further object is to provide a switch mechanism having the above characteristics wherein the operating handle for the improved mechanism serves as a retaining and protecting housing for the switch-actuating mechanism.

Switches enclosed in boxes operated by a simple bent-rod lever projecting exteriorly of the box have been used extensively in lighting and power-circuit installations. Such switches and boxes are more or less standardized, the switch being of the knife-blade type and adapted to be opened by a handle-actuating lever. Consequently, the opening movement of the switch of this type is comparatively slow, and destructive arcing results.

To obviate this condition and to increase the safety of operation, the switch blade should be quickly moved to open and to closed position with a snap action. The advantages of a quick-make and a quick-break switch are well recognized in the art and, for certain classes of installations, wiring regulations require that the switches be snap-actuated. In installations employing the ordinary knife-blade switches, such requirements necessitate the removal of the old switches and replacement of the switches of the quick make-and-break type, which involves considerable expense, inconvenience and delay.

An object of this invention is to provide a quick make-and-break attachment for switch boxes that can be readily attached to standard boxes by simply replacing the old handle with a crank arm, and attaching a handle member to the box that contains the necessary mechanism for imparting a snap action to the switch shaft.

These and other objects, which will be made apparent throughout the further description of the apparatus, are attained by means of the apparatus embodying my in-

vention herein described and illustrated in the accompanying drawings, wherein:—

Figure 1 is a transverse vertical section through a switch box having my switch-actuating mechanism attached thereto.

Fig. 2 is a section through the switch-operating mechanism taken on the line II—II of Fig. 1.

Figs. 3 and 4 are front and side elevations, respectively, of the switch-operating mechanism.

Referring to the drawings, the apparatus includes a switch box 5 in which a knife-blade switch 6 is mounted. The box is provided with a cover 7, and the switch 6 is actuated by means of a bent-rod operating shaft 8, having one end pivoted to a side wall of a box and the other end projecting through the opposite side wall thereof. The projecting end of the shaft is provided with a square portion 9 to which an operating handle is usually attached. The switch and box above described are of a standard type well known to the art and, therefore, a detailed description thereof will not be necessary.

In practicing my invention, where the device is applied to a standard switch box, as above described, the usual handle is first removed, and a crank member 10 is so placed upon the square portion 9 of the switch shaft that it rotates with the shaft. A crank pin 11 is carried by the free end of the crank member 10, and the edge of the crank member is provided with projecting teeth 11a and 12 that are adapted to be engaged by pawl members 13 and 14, respectively. The outer end of the crank member is provided with an enlarged head portion which forms a pair of stop faces 15 and 16 that respectively engage the pawl members 13 and 14. The pawl members 13 and 14 are pivoted upon pins 17 and 18, respectively, which are mounted on a plate 19 that is secured to the side of the box by means of screws 20. The pawls are normally held in engagement with the edges of the crank member by a bent-leaf spring 21 that is inserted between opposite extensions 22 and 23 of the pawl member and lodged in the notches 24 thereof.

The crank arm is operated by means of an operating lever 25 that is provided with a cylindrical casing 26 which is rotatably mounted upon a bracket 27 that is secured to the side of the box by means of screws 27'. The

A fixed pin or shaft 28 is riveted to the bracket 27 and is axially aligned with the axis of rotation of the switch shaft 8 and serves as a shaft upon which the casing 26 rotates. The casing is held in assembled relation with the fixed shaft by means of a washer 29 and a pin 30. The casing completely surrounds the crank member and the pawl members 13 and 14 and serves as a protecting housing, as well as a part of the switch-operating mechanism.

The casing 26 is provided with an integral central hub 31 through which the shaft 28 extends. This hub carries an integral radially-disposed web 32 that is yieldingly connected to the crank pin 11, through the medium of a helical spring 33, that is so coiled within the casing 26 that its ends 34 and 35 engage opposite sides of the web 32 and the pin 11, and, by reason thereof, normally hold these elements between them in a predetermined relation with respect to one another. Lugs 36 and 37 are cast integral with the casing and engage the pawl extensions 22 and 23 when the casing is turned about its axis and serve to move the pawls 13 and 14 out of engagement with the teeth 11 and 12, respectively.

As shown in Fig. 2, the elements constituting the switch-actuating mechanism are in the relative positions occupied when the switch 6 is in closed position. The switch has been thrown from "off" to "on" position and its movement has been arrested by reason of the engagement of the stop face 16 with the pawl 14. The pawl 13, at such time, falls into engagement with the tooth 11 and prevents counter-clockwise rotation of the crank member 10.

When the handle 25 and the casing 26 are turned counter-clockwise, the end 34 of the spring 33 is moved in the same direction while the crank member is held stationary by the pawl member 13. The end 35 of the spring tends to force the crank member 10 to follow the movement of the casing 26 and actually causes it to follow the casing with a snap action the moment that the pawl 13 is moved out of engagement with the tooth 11a as a result of the movement of the extension 22 by the lug 33 carried by the casing. The crank member continues to turn until the stop face 15 engages the pawl 13.

At this time, the pawl 14 moves into engagement with the tooth 12 of the crank member 10 and prevents clockwise movement thereof until the lug 37 trips the pawl member during the reverse or closing movement of the operating lever.

It will be apparent from the foregoing that the switch 6 is moved to open and to closed position with a snap action. However, if the switch becomes stuck in either open or closed position and the tension of

the spring be insufficient to dislodge the switch, the switch may be positively actuated by so moving the handle 25 that the lugs 36 and 37, as the case may be, engage the faces 15 and 16 respectively of the 70 crank member 10 to positively actuate the crank member. In the event of a broken spring, the switch may be positively actuated by the above procedure.

While the device has been described as 75 being particularly well adapted for application to standard switches for the purpose of imparting snap action thereto, it will be understood that the device is highly practicable as an article of manufacture 80 wherein the operating mechanism is combined at the factory with various forms of switch boxes and switches.

While I have described and illustrated but one embodiment of my invention, it 85 will be apparent to those skilled in the art that various modifications, changes, substitutions, additions and omissions may be made in the apparatus described without departing from the spirit and scope of the 90 invention, as set forth by the appended claims.

I claim as my invention:

1. The combination with a switch box and a switch shaft projecting from a wall thereof, of a shaft secured to the said wall and aligned with the switch shaft, an operating enclosure member mounted upon the second shaft exteriorly of the box and having means therein for effecting quick operation of the 100 switch shaft in response to a predetermined movement of the operating enclosure member.

2. The combination with a switch box and a switch shaft projecting from a wall thereof, of an operating enclosure member pivotally mounted on the said wall and exteriorly of the box and means within the enclosure member for effecting quick operation of the switch shaft in response to a predetermined 105 movement of the enclosure member.

3. The combination with a switch box and a switch shaft projecting from a wall thereof, of an operating enclosure member pivotally mounted on the wall exteriorly of the 115 box and having an elastic lost-motion connection with the said shaft, and means within the enclosure member for controlling the said shaft for permitting movement thereof in response to a predetermined movement of 120 the said enclosure member.

4. The combination with a switch box and a switch shaft projecting therefrom, of an operating means for the said shaft including a casing pivotally mounted exteriorly of the 125 box and having therein an elastic lost-motion connection with the said shaft, means for controlling the said shaft located within the said casing for permitting movement of the said shaft in response to a predetermined 130

movement of the said casing and means whereby the said casing may be turned.

5. The combination with a switch box and a switch shaft projecting therefrom, of a shaft secured to the box and alined with the switch shaft, an operating member pivoted exteriorly of the box and upon the second shaft, a floating spring yieldingly connecting the switch shaft to the operating member 10 whereby the switch shaft is moved by the operating member, and means for retaining the switch shaft in predetermined positions, irrespective of movement of the operating shaft within predetermined limits of movement and for releasing the said shaft when the operating shaft has moved beyond the said predetermined limits of movement.

6. Switch mechanism comprising a box, a switch shaft projecting therefrom, a bracket 20 secured to the box, a casing rotatably mounted exteriorly of the box and upon the bracket, a floating spring within the casing yieldingly connecting the casing and the switch shaft, and means for controlling the 25 movement of the said shaft, actuated by the casing.

7. Switch mechanism comprising a box, a switch shaft, a bracket mounted upon the box, a casing rotatably mounted on the 30 bracket, a floating spring within the casing yieldingly connecting the casing and the switch shaft, and means for controlling the movement of the said shaft movably mounted on the box and operable by the said 35 casing.

8. Switch mechanism comprising a box, a switch member, a casing rotatably mounted on the box, a spring connecting the casing to the switch member for normally retaining 40 the said shaft and the casing in a predetermined relation, and means within the casing and pivotally mounted on the box and operable by the casing for controlling the movement of the said shaft.

45 9. Switch mechanism comprising a box, a

switch member projecting therefrom, a bracket secured to the exterior of the box, a casing rotatably mounted on the said bracket, a spring yieldingly connecting the casing to the switch member for normally retaining the member and the casing in a predetermined relation, and means mounted on the box and operable by the casing for controlling the movement of the said shaft.

10. Switch mechanism comprising a box, a switch shaft projecting therefrom, a crank member mounted on the projecting end of the switch shaft and movable therewith, a casing rotatably mounted exteriorly of the box, a spring within the casing yieldingly connecting the casing to the crank member for normally retaining the shaft and the casing in a predetermined relation, and pawl members yieldingly held in engagement with the crank member for controlling the movement thereof and operable by the said casing.

11. Switch mechanism comprising a box, a switch shaft, a casing rotatably mounted on the box, a floating spring within the casing yieldingly connecting the casing and the switch shaft, means for controlling the movement of the said shaft movably mounted on the box and operable by the said casing, and means whereby the switch is positively actuated by the said casing.

12. The combination with a switch box and a switch shaft projecting therefrom, of an operating means for the said shaft including a rotatable casing pivotally mounted exteriorly of the box and having therein an elastic lost-motion connection with the said shaft, and means for controlling the said shaft including a pair of pawl members pivoted to the said box and operable to release the shaft by the casing when the latter has been rotated a predetermined distance.

In testimony whereof, I have hereunto subscribed my name this 14 day of October, 1920.

OLIVER S. JENNINGS.
